[57] CLAIM

The ornamental design for an IC socket panel or the like, as shown and described.

DESCRIPTION

FIG. 1 is a top and left front perspective view of an IC socket panel or the like with a lever engaged therewith, showing my new design;

FIG. 2 is a top and left front perspective view thereof with the lever released and rising therefrom;

FIG. 3 is a bottom and left front perspective view thereof;

FIG. 4 is a top plan view thereof on a reduced scale;

FIG. 5 is a front elevational view thereof on a reduced scale;

FIG. 6 is a right side elevational view thereof on a reduced scale; and

FIG. 7 is a rear elevational view thereof.

FIG.1

FIG. 2

FIG. 3

FIG. 4

FIG. 5
